ATTORNEYS

UNITED STATES PATENT OFFICE.

FRANCIS B. LADE VEZE, OF PORTLAND, OREGON.

TOWEL-HOLDER.

1,369,310.

Specification of Letters Patent. Patented Feb. 22, 1921.

Application filed March 1, 1920. Serial No. 382,333.

To all whom it may concern:

Be it known that I, FRANCIS B. LADE VEZE, a citizen of the United States, residing at Portland, in the county of Multnomah and State of Oregon, have invented certain new and useful Improvements in Towel-Holders, of which the following is a specification.

This invention relates to towel racks or holders and has for its object to provide a means for holding the towels in place upon the rack or bar.

A further object is to provide a means whereby several towels may be held upon the bar in a manner that the withdrawal of one will not dislodge the others.

A further object is to provide a means whereby a number of towels may be held upon a bar and against accidental removal therefrom, and in the event that other towels are laid upon the first mentioned towels the removal of an upper towel will not remove the lower ones accidentally.

A further object is to provide a means for holding towels of varying thickness upon a towel bar without strain.

A further object is to provide a means for holding towels that has no projecting sharp edges that might tend to mutilate the towels, that may be made removable if desired, and that is cheap to manufacture, efficient in operation, and ornamental in effect.

With these and other objects in view reference is now had to the accompanying drawings in which—

Figure 1 is a front elevation of a towel bar showing holders attached thereto;

Fig. 2 is an enlarged end elevation of a clamp;

Fig. 3 is a side elevation of the holder as attached to this form of clamp;

Fig. 4 is an enlarged end elevation of a modified form of clamp;

Fig. 5 is a side elevation of the holder attached to this form of clamp;

Fig. 6 is an end elevation showing a jaw member attached to the bar without a clamp;

Fig. 7 is a side elevation thereof; and

Fig. 8 shows the design of a plurality of holders attached to the bar.

Having reference to the drawings like numerals refer to like parts throughout and

the numeral 1 refers to a towel bar of the usual type and carrying a single holder 2 and a double holder 3 with a towel 4 in place under one of the yielding jaw members which constitutes a part of the holder. 55

The jaw member consists of a shank portion 5 and an upwardly curved end portion 6 which is curved to conveniently receive the towel or other article to be held. The shank portion is held positioned normally above the bar to provide a space therebetween which will conveniently receive the 65 article without strain to the jaw member.

The jaw member may be attached to the bar in any convenient manner such as a clamp 7 consisting of a yoke to which the jaw member will be rigidly attached, and 70 which will be clamped upon the bar by means of the bolt 8 as shown in Fig. 2. Figs. 4 and 5 show a slight modification of the clamp while Figs. 6 and 7 show the jaw member attached directly to the bar by 75 means of the bolt 9.

In Fig. 8 a slight variation occurs; in this design there is a succession of jaw members attached to a cross bar 10 which in turn is 80 suitably attached to the bar 1.

By shortening the jaw members so that only a small portion of the article is clamped it is obvious that many towels may be held upon the bar; and by the addition of more towels laid loosely upon those which are 85 held by the clamps, the bar will hold a vast number of towels and the removal of the topmost towel will not disturb the others.

In use the device is conveniently attached to the bar by any desired means and the 90 towel (or other article) is thrown over the bar and pressed to the left (or right as the case may be) passing under the jaw member, the operation being continued until all the jaw members are full or until the required number of articles are placed upon the bar. 95

It must be understood that slight modifications may be resorted to without departing from the spirit of the invention. 100

Having thus described my invention, I claim—

1. In a towel holder, in combination with a towel bar, a cross bar, a plurality of vertically operable yielding jaw members, rigidly attached to said cross bar, flexible 105

clamps rigidly attached to said cross bar for engagement with said towel bar, and a means for attaching said clamp rigidly and removably to said towel bar.

- 5 2. In a towel holder, in combination with a towel bar, a cross bar, a vertically operable yielding jaw member, rigidly attached

to said cross bar, a flexible clamp rigidly attached to said cross bar for engagement with said towel bar, and a means for attaching said clamp rigidly and removably to said towel bar. 10

In testimony whereof I affix my signature.
FRANCIS B. LADE VEZE.
